ICE TRAY

Clifford R. Carney, Detroit, Mich.

Application August 11, 1939, Serial No. 289,517

10 Claims. (Cl. 62—108.5)

This invention relates to ice trays and more particularly to means for releasing ice trays or pans from the freezing compartment of an ice forming machine.

Heretofore considerable difficulty has been experienced in effecting the removal of the ice tray or pan from the freezing compartment because of the fact that a thin film of moisture, between the bottom of the tray and the supporting surface of the refrigerating compartment, freezes whereupon it is impossible to remove the tray from the supporting surface until a sufficient force is applied to break the ice bond.

An object of this invention is to provide means whereby the film of ice between the bottom of the ice forming tray and the supporting surface may be readily broken.

Another object of the invention is to provide readily accessible manually operable means whereby a portion of the tray may be cammed upwardly to break the film of ice between the tray and the supporting surface.

A further object of the invention is to provide hinged actuating means to break the tray loose from the supporting surface in the refrigerating compartment.

A still further object of the invention resides in the provision of novel manually operable means associated with the forward portion of the tray and cooperating with the tray supporting surface to release the tray from said supporting surface.

Yet a still further object of the invention is to provide improved manually operable release means having novel stop means to prevent the release mechanism from interfering with replacing the tray in the freezing compartment of the refrigerating unit.

Other objects and advantages of this invention will be apparent from the following detailed description, considered in connection with the accompanying drawing, submitted for purposes of illustration only and not intended to define the invention, reference being had for that purpose to the subjoined claims.

In the drawing wherein similar reference characters refer to similar parts throughout the several views:

Fig. 1 is a side elevation, partly in section, of an ice tray embodying the present invention, showing the releasing mechanism in the inoperative position;

Fig. 2 is a front elevation of the device illustrated in Fig. 1;

Fig. 3 is a fragmentary sectional view similar

to a portion of Fig. 1 showing the release mechanism in the operative position;

Fig. 4 is a front elevation similar to Fig. 2 showing a modified form of the invention;

Fig. 5 is a side sectional elevation similar to a portion of Fig. 1, showing a still further modified form of the invention;

Fig. 6 is a view similar to Fig. 5 showing a further modified form of the invention, and

Fig. 7 is a front elevation of the form of the invention illustrated in Fig. 6.

Before explaining in detail the present invention it is to be understood that the invention is not limited in its application to the details of construction and arrangement of parts illustrated in the accompanying drawing, since the invention is capable of other embodiments and of being practiced or carried out in various ways. Also it is to be understood that the phraseology or terminology employed herein is for the purpose of description and not of limitation, and it is not intended to limit the invention claimed herein beyond the requirements of the prior art.

Referring now to Figs. 1 to 3, which illustrate one desirable embodiment of the invention, an ice tray or pan 10 having a bottom wall 11, and side walls 13, is positioned on a supporting surface 12 of a freezing compartment or evaporator. A generally transversely extending inverted channel 14 is formed in the bottom wall 11 adjacent the front end wall 16 of the tray. The side walls 13 are formed with downwardly extending rigidifying lips 15, and the front wall 16 is provided with a downwardly directed rigidifying lip 18. An actuating lever 20 may be pivotally mounted to the lip 18 as by pins 22 as illustrated, and preferably includes a forwardly disposed manually operable hook portion 24. A generally downwardly and rearwardly extending lever 26 is pivotally mounted to the lever 20 by a pin 28 and is provided with a camming surface 30 adapted to lie within a portion of the transversely extending inverted channel 14 as illustrated. A stop 32 carried by or formed in the lever 20 is adapted to engage a portion of the lever 26 to prevent undesirable downward movement of the lever 26 relative to the tray 10. The lip portion 18 is provided with a downwardly extending directed portion to act as a stop member 34 to limit undesirable outward movement of the lever 20 away from the tray 10.

In the operation of this device, assume that it is desired to remove the tray 10 and its frozen contents from the supporting surface 12 of the freezing compartment of the refrigerator. The

manually operable hook portion 24 may be grasped and pulled forwardly in the direction to remove the tray from the freezing compartment. Forward movement of the hook portion 24 operates through the pivotal connections 22 and 28 to exert a forwardly directed force on the lever 26 to move the camming surface 30 forwardly within the channel portion 14 of the tray to engage the surface 36 of the tray thereby camming it upwardly to break the bond between the tray 10 and the surface of the supporting member 12 as more clearly illustrated in Fig. 3. When the frozen contact between the tray 10 and the surface 12 is broken, the tray 10 may be readily removed from the freezing compartment by a continued outward pull on the hook portion 24. To replace the tray 10 into the freezing compartment, the tray 10 may be grasped at the forward portion of the lip 18 and the lever 24 moved in the clockwise direction as viewed in Figs. 1 to 3 toward the tray whereupon the stop 32 urges the lever 26 to move the camming surface 30 into the channel 14, whereupon the tray may be readily slid into the freezing compartment as illustrated in Fig. 1.

The modified embodiments illustrated in Figs. 4, 5 and 6 and 7 are similar in many respects to the embodiment illustrated in Figs. 1 to 3; corresponding parts have therefore been given corresponding reference numbers with the addition of 100 in each case.

In the embodiment illustrated in Fig. 4, the transversely extending channel 14 of Fig. 1 is replaced by the short transversely extending channel 150 interposed between the side walls 113 of the tray 110. In this embodiment, the lever 126, and the surface 130 are proportioned to be received within the channel 114 formed in the lower portion of the tray 110. The operation of this embodiment is substantially similar to that of the embodiment illustrated in Figs. 1 to 3.

In Fig. 5 embodiment, the upwardly extending front wall portion 260 of the tray is provided with 45 a downwardly extending actuating portion 262 which terminates in a generally transversely extending camming surface 264 adapted to be received within the channel portion 214 of the tray 210. The actuating portion 262 is provided with 50 a handle 266 which may be pulled forwardly to enable the camming surface 264 to engage the surface 236 of the channel 214 to release the tray 210 from the supporting surface 212. In this embodiment the segment 264 is maintained in 55 nested relation within the channel 214 by the resiliency of the walls 260 and lip 262 whereby the tray 210 may be readily inserted into the freezing compartment of the refrigerating unit.

The embodiment illustrated in Figs. 6 and 7 60 is similar in many respects to that of Fig. 5. It will be noted however that a manually operable member or handle 370 is formed by shearing a portion of the metal of the portion 362 65 and rolling it upwardly to form the handle member. In this embodiment a pair of spaced camming surfaces 364 are provided on each side of the handle 370.

I claim:

70 1. An ice tray having a bottom wall adapted to rest on a supporting surface, side and end walls, a generally transversely extending channel formed in the bottom wall adjacent one of the end walls, and means carried by said end wall adapted to engage the bottom wall and

supporting surface to separate the bottom wall from the supporting surface.

2. An ice tray having a bottom wall adapted to rest on a supporting surface, side and end walls, a generally transversely extending channel formed in the bottom wall adjacent one of the end walls, and manually operable means carried by said end wall and having a member adapted to lie within said channel to engage the bottom wall and supporting surface to separate the bottom wall from the supporting surface. 5

3. An ice tray having a bottom wall adapted to rest on a supporting surface, an end wall, a generally transversely extending channel portion between the bottom wall and end wall, and longitudinally movable means carried by the end wall and adapted to lie within said channel to engage a portion of the channel and the supporting surface to release the bottom wall from the supporting surface. 15

4. An ice tray having a bottom wall adapted to rest on a supporting surface, an angularly inclined end wall, a generally transversely extending channel between the bottom wall and end wall, and means pivotally mounted on the end wall having a portion adapted to lie within said channel to engage a portion of the channel and the supporting surface to release the bottom wall from the supporting surface. 20

5. An ice tray having a bottom wall adapted to rest on a supporting surface, a transversely extending channel portion formed in the bottom wall adjacent one of its ends, an end wall carried by the bottom wall adjacent the channel portion, a camming member adapted to lie within said channel portion, and manually operable means pivotally mounted to the end wall and to said camming member to actuate the camming member to release the tray from the supporting surface. 30

6. An ice tray having a bottom wall adapted to rest on a supporting surface, a transversely extending channel portion formed in the bottom wall adjacent one of its ends, an end wall carried by the bottom wall adjacent the channel portion, a camming member adapted to lie within said channel portion, manually operable means pivotally mounted to the end wall and to said camming member to actuate the camming member to release the tray from the supporting surface, and stop means to limit the movement of the camming member and the manually operable means. 45

7. An ice tray having a bottom wall adapted to rest upon a supporting surface, an end wall, an inverted generally transversely extending channel section between the bottom wall and the end wall, a longitudinally movable camming member carried by the end wall and adapted to lie within said channel to exert a force to separate the tray and supporting surface, and manually operable means to move the camming member longitudinally of the tray. 55

8. An ice tray having a bottom wall adapted to rest upon a supporting surface, an angularly inclined end wall, an inverted generally transversely extending channel section between the bottom wall and the end wall, spaced camming surfaces carried by the end wall and adapted to lie within said channel to exert a force to separate the tray and supporting surface, and manually operable means between the spaced camming surfaces to actuate the camming surfaces to release the tray from the supporting surface. 60

9. An ice tray having a bottom wall adapted 70

to rest on a supporting surface, an angularly inclined end wall, a generally transversely extending inverted channel in the bottom wall adjacent said end wall, the downwardly directed portion of the channel adjacent the angularly inclined end wall lying above the bottom surface of the bottom wall, and an implement carried by the end wall and projecting between said portion of the channel and the supporting surface 10 and movable longitudinally of the tray to release the tray from said surface.

10. An ice tray having a bottom wall adapted to rest on a supporting surface, a transversely extending channel portion formed in the bottom wall adjacent one of its ends, an end wall carried by the bottom wall adjacent the channel 5 portion, a camming member adapted to lie within said channel portion, and manually operable means associated with the end wall and camming member to actuate the camming member to release the tray from the supporting surface. 10
